UNITED STATES PATENT OFFICE.

THOMAS H. DOWNIE, OF SAN FRANCISCO, CALIFORNIA.

FOUNDRY-FLASK.

1,092,636.

Specification of Letters Patent.

Patented Apr. 7, 1914.

Application filed May 7, 1912. Serial No. 695,694.

To all whom it may concern:

Be it known that I, THOMAS H. DOWNIE, citizen of the United States, residing at San Francisco, in the county of San Francisco and State of California, have invented certain new and useful Improvements in Foundry-Flasks, of which the following is a specification.

This invention relates to improvements in foundry flasks and has for its object the provision of a flask which may be easily knocked down and secured in a small compass when not in use and which may be as easily set up for use and firmly secured in its operative position.

A further object of the invention is to provide a construction by which the extension of the flask to any desired dimensions may be easily accomplished.

20 A further object of the invention is to provide a cross bar of novel construction which may be readily secured at any point in the flask, and finally the object of the invention is to improve generally the construction of foundry flasks so as to increase the efficiency of the same.

All these stated objects, and such other incidental objects as will hereinafter appear, are obtained in the devices, which will 30 be hereinafter fully set forth, and are illustrated in the accompanying drawings, in which:-

Figure 1 is a perspective view of a flask constructed in accordance with my invention, showing the same set up for use. Fig. 2 is a side view showing the manner of connecting several sections to extend the flask to any degree. Fig. 3 is a perspective view of one of the sections detached. Fig. 4 is a 40 detail sectional view on the line 4-4 of Fig. 2 showing the manner of connecting several sections together. Fig. 5 is a detail view of the locking pin employed to secure the sections together. Fig. 6 is a detail sectional view showing the manner of securing the cross bar in position. Fig. 7 is a detail perspective view showing the construction of the end of the cross bar. Fig. 8 is a detail view of a clip which may be applied to the 50 sections when the same are made of wood. Fig. 9 is a detail view showing the said clip applied to a section.

In carrying out my invention, I employ a plurality of side members or sections each 55 consisting of a base, wall or plate 1, from the edges of which flanges 2 project out-

wardly. The base or plate 1 is generally of an oblong form and at one end is provided with an extension or tongue 3 and at the opposite end with a corresponding recess or notch 4, the flanges 2 following the outline of the edges of the plate and consequently defining the said notch and the said tongue, as will be readily understood on reference to Fig. 3. In the flanges 2, at the sides of the notch 4, are grooves or recesses 5 and upon the outer faces of the said flanges, at the sides of the tongues 3, are ribs 6 which are adapted to engage said grooves 5 in the adjacent section when the sections are arranged to form an extended flask. The width of the tongue and the width of the notch should be substantially equal so that when the sections are disposed at a right angle to each other, the tongue will project 70 through the recess or notch of the meeting section, and the ribs 6 will then fit against the edges of the flanges 2 at the sides of the notch 4 and extend across the ends of the grooves 5, as shown in Fig. 1.

At regular intervals throughout the base or plate 1, I form slots 7 which are formed by boring through the plate intersecting circular openings, so that the slots will have round ends with opposed teeth or projections 8 between the said ends. Similar slots are formed in the flanges 2 at the ends of the tongues 3 and the notches 4, as shown at 9, these slots 9 being so located that their lower walls will lie in the plane of the face of the plate 1, so that a fastening key inserted therethrough will bear against the said plate. Slots 10, similar in all respects to the slots 9, are formed through the flanges 2 at the sides of the tongues 3 and notches 4 to likewise 95 receive fastening pins. In the outer side faces of the flanges 2 extending along the side edges of the sections, I form grooves 11 which have their walls overhanging, so that when the sections are placed together with 100 the grooves 11 of adjacent sections registering, the registering grooves will form slots of the same outline as the slots 7, 9 and 10, as will be readily understood on reference to Fig. 2. To reinforce the flanges at the 105 points where these grooves are formed therethrough, I provide bosses or offsets 12 on the inner faces of the flanges in the planes of the said grooves and similar offsets 12^a bridge the grooves 5, as clearly shown.

To secure adjacent or meeting sections together, I employ a locking pin, shown in de-

tail in Fig. 5, said pin 13 consisting of a wedge having longitudinal grooves 14 disposed centrally in its opposite faces between its converging sides, which sides are convex 5 whereby the cross section of the wedge or locking pin will have the same outline as the slots in the sections in which they are engaged and it will be understood, of course, that the longitudinal walls of the slots and 10 grooves converge in the same degree that the pin tapers. At the wider end of the locking pins are openings 15, which may be engaged by any suitable withdrawing implement when it is desired to knock down the flask, or 15 for any other reason it is necessary to withdraw the pins.

The cross bar 16 is in the form of an oblong plate having slots 17 formed therethrough at regular intervals throughout its 20 extent, said slots being of the same form as the slots 7, 9 and 10 in the sections, as shown. The ends of the cross bar are constructed with series of longitudinal tapered tongues 18, provided on their side edges with ribs 19, 25 the said tongues being spaced apart at intervals equal to the intervals between adjacent slots in the bases of the sections, so that wedges or locking pins may be inserted through the slots 7 in the sections to engage 30 between the said tongues and thereby secure the cross bar in position. The cross bar, it will be readily seen, may be secured at any point, either longitudinally or transversely, of the flask and one or more may be employed according to the exigencies of the 35 work being done.

The sections will preferably be made of metal, as the requisite strength can be thereby attained without great bulk, but it may 40 sometimes be advantageous to employ wood as the material of which the sections are made, and, in such event, I prefer to utilize the clip shown in Figs. 8 and 9, consisting of a metal plate 20 having a transverse offset 45 21 at its center on one side and provided in its opposite side, in the same transverse plane as said offset, with a groove 22 having its edges overhanging, as clearly shown. These clips will be secured in the flanges 2 of the 50 sections so that the outer faces of the clips and the flanges will be flush, and the grooves 22 will receive the locking pins in the same manner as the grooves 11 receive the same, so that the wearing away of the side walls of 55 the grooves will be obviated and the life of the sections prolonged.

In assembling the sections to form a flask, the tongue 3 of one section is engaged in or inserted through the notch 4 of the meeting 60 section so as to pass therethrough at a right angle, as clearly shown in Fig. 1, in which position the ribs 6 will engage the outer edges of the flanges 2 at the sides of the notch, so as to maintain the relative positions of the sections, and the sections are

then secured together by driving wedges or locking pins 13 through the slots formed in the flanges at the end of the tongue and at the end of the plate extending from the sides of the notch to the side edges of the 70 plate. The sections will thus be locked together so that displacement and disengagement thereof cannot occur and the founding operations may be performed without any fear of the flask collapsing and permitting 75 the molten metal to escape. The cross bars or boards 16 are set up on edge between parallel sections with the tapered tongues 18 bridging the slots in the bases of the sections, and locking pins or wedges are then 80 inserted through said slots between the said tongues, so as to engage the same and bind between them so that the cross bars will be firmly secured in place.

My improved device is exceedingly simple 85 in its construction and may, obviously, be set up or knocked down within a few minutes.

The flask may be made of any desired size by placing the sections end to end with the tongue on one section filling the notch in the meeting section and the ribs 6 engaging the grooves 5, as shown in Fig. 2. Locking pins or wedges are then inserted through the registering slots in the flanges of the 90 sections to lock the sections against transverse displacement and through the registering grooves 11 to lock them against longitudinal displacement. The engaging tongues and notches form efficient aids in 95 assembling the sections and holding them in 100 their relative positions until the locking pins are driven home.

Having thus described my invention, what I claim as new, is:—

1. A flask composed of sections each having a tongue projecting from one end edge and provided at its opposite end with a notch opening through both side faces of the section whereby any two sections may be fitted 105 together in alinement with the tongue of one section fitting in the notch of a meeting section or may be placed at right angles with the tongue of one section passing transversely through the notch of the meeting section.

2. A flask composed of sections each having a tongue at one end provided upon its upper and lower sides with transverse ribs, the opposite end of the section being provided with a notch opening through the opposite side faces of the section and provided in its upper and lower walls with transverse recesses whereby two sections may be fitted together with the tongue of one section fitting in the notch of a meeting section and the ribs on said tongue engaging the recesses in the upper and lower walls of said notch or with the tongue of one section passing transversely through the notch of 120 125 130

a meeting section and the ribs on said tongue bearing against the outer side face of the meeting section above and below said notch.

3. A flask composed of sections each having a tongue at one end and a notch at the opposite end and provided with external flanges around said tongues and notches and having slots through said flanges and said tongues, and tapered locking pins adapted to be inserted through the said slots to lock the sections together.

4. A flask composed of sections having flanges on their outer sides and grooves in the outer faces of said flanges having overhanging edges, and tapered locking pins adapted to engage the grooves of adjacent flanges to lock adjacent sections together and shaped to fit snugly in said grooves.

5. A flask section comprising a base having a notch at one end and a tongue at the opposite end, and a flange defining the side and end edges of the plate, grooves being formed in the outer side of the flange at the

sides of the notch and ribs being formed on the outer sides of the flange at the sides of the tongue.

6. A flask comprising meeting members provided with registering slots having converging walls and having round ends and opposed projections on their sides, and tapered locking keys adapted to pass through said slots to lock the sections together, said keys having round edges and longitudinal grooves to engage the projections in the slots.

7. A flask comprising superposed sections having transverse grooves in their upper and lower edges, and locking pins engaging adjacent grooves in the meeting edges of the sections to secure the sections together.

In testimony whereof I affix my signature in presence of two witnesses.
